INTERLOCKING CONTROL APPARATUS

Ronald A. McCann, Swissvale, Pa., assignor to
The Union Switch & Signal Company, Swiss-
vale, Pa., a corporation of Pennsylvania

Application June 8, 1944, Serial No. 539,234

6 Claims. (Cl. 246—134)

My invention relates to interlocking control apparatus, and particularly to interlocking control apparatus in which manual control devices such for example as push buttons, which are free to be operated at any time, are provided for controlling the signals and track switches of a railway interlocking layout.

In interlocking plants having overlap control of signals, such for example as in interlocking plants employing train stops, it is necessary to extend the locking distance of certain switches or crossovers in order to prevent the operation of such switches or crossovers from causing an approach signal to be returned to the stop indication after it has been cleared.

One feature of my invention is the provision of means for storing the control for a route when a switch or crossover in the route is locked because the extended locking section is occupied by a car or train while the section in which the switch or crossover is located is unoccupied.

I shall describe one form of apparatus embodying my invention, and shall then point out the novel features thereof in claims.

In the accompanying drawings, Figs. 1a to 1e, inclusive, are diagrammatic views showing one form of apparatus embodying my invention, in which Fig. 1a shows a layout of switches and signals in an interlocking plant, together with switch and signal operating circuits, signal control circuits, and control means for a switch indication relay; Fig. 1b shows route selector circuits for the layout of Fig. 1a controlled by manual control devices shown in Fig. 1d; Fig. 1c shows circuits for controlling switch locking relays and switch control and indication relays, and also an approach locking relay associated with a given approach signal; Fig. 1d shows a track model or diagram for the interlocking layout of Fig. 1a divided into indication sections, and shows manually controllable push buttons arranged in the track model at points corresponding to the signal locations; and Fig. 1e shows circuits for controlling indication lamps for two of the indication sections of Fig. 1d.

Similar reference characters refer to similar parts in each of the views.

In each of the views, contacts operated by the various relays or other devices are identified by numbers, such numbers having distinguishing prefixes from which they are separated by a dash when the contacts are shown apart from the relay by which they are operated. The prefix for each of these contact numbers comprises the reference character for the respective relay by which

the contact is operated. For example, contact 1W—97 shown adjacent the symbol for mechanism A1M in Fig. 1a is identified by the number 97 separated by a dash from the prefix 1W which is the reference character for relay 1W by which this contact is operated. Some contacts, shown in the drawings, but which are included only in circuits which are not traced in this specification, are identified by the reference character for the relay by which they are operated, followed by a dash, without a number after the dash. For example, contact 1ANS—, shown in the stick circuit for relay 2XS in Fig. 1b, is identified by the reference character 1ANS for relay 1ANS by which this contact is operated, followed by only a dash.

Referring first to Fig. 1a, a track layout is shown, in which two parallel tracks are interconnected by a crossover including track switches designated by the reference characters A1 and B1. In order to simplify the drawings, each track, comprising two parallel series of track rails, is represented by a single line.

These tracks are divided by insulated joints 7 to form switch sections designated by the reference characters A1T and B1T in which switches A1 and B1, respectively, are located, extended locking sections designated by the reference characters 6T and 8T, and approach sections designated by the reference characters 10T and A10T associated with an approach signal 10. Each of these track sections is provided with a track circuit including a suitable source of current such as a battery 9, connected across the rails adjacent one end of the section, and a track relay, designated by a reference character which is the same as the reference character for its section except that it includes the letter R instead of the letter T, connected across the rails adjacent the opposite end of the section.

Traffic movements toward the left, as shown in the drawings, which I shall assume is the southbound direction, over switches A1 and B1, are governed by home signals designated by the reference characters 6 and 8, respectively. An approach signal 10 is provided for signal 6. Traffic movements in the opposite or northbound direction, over switches A1 and B1, are governed by signals 2 and 4, respectively. The signals may be of any suitable design, such for example as the semaphore or the searchlight type.

Switches A1 and B1 are operable to their normal positions, in which they are shown in the drawings, or to the opposite or reverse positions, by mechanisms designated by the reference characters A1M and B1M, respectively. Mechanisms

A1M and **B1M** are in turn controlled by a polarized switch control relay **1W**, shown in Fig. 1c.

A polarized switch indication relay **1P** is controlled similarly to relay **1WP** described in Letters Patent of the United States No. 2,301,297 granted November 10, 1942 to Lloyd V. Lewis for Railway traffic controlling apparatus, so as to be energized by current of normal polarity when switches **A1** and **B1** are both in their normal positions, and to be energized by current of reverse polarity when switches **A1** and **B1** are both in their reverse positions.

Approach signal **10** is operated by a circuit including a front contact of a signal relay **10H**. This relay is controlled by a manually operable lever **10V** having a normal position **n** and a reverse position **r**, by extended locking section track relay **6R** when switches **A1** and **B1** are in the normal position, by extended locking section track relay **8R** and switch section track relay **B1R** when switches **A1** and **B1** are in the reverse position, and also by switch section track relay **A1R** and by approach section track relay **10R**.

Referring now to Fig. 1b, circuits are here shown for controlling route selector relays and exit stick relays by manual route control push buttons which are shown in Fig. 1d designated by the reference character **P** preceded by the reference character for the signal for the corresponding route end. Each of the push buttons operates a circuit controller which is of the push-pull type, such for example as shown in Letters Patent of the United States No. 2,295,301 granted September 8, 1942 to W. E. Smith for Circuit controllers. Each of these controllers is biased to a mid stroke position, and has a normally open contact and a normally closed contact such for example as contacts **42** and **96**, respectively, of controller **4P** shown at the left-hand end of Fig. 1b. Contact **42** becomes closed when button **4P** is pushed in, and contact **96** becomes opened when button **4P** is pulled out.

Each exit stick relay is designated by the reference character **XS** preceded by a number corresponding to that of the push button by which it is controlled. The other relays shown in Fig. 1b are route selector relays designated by the reference character **N** or **S** for northbound or southbound, respectively, preceded by reference character **N** or **R** for the normal or the reverse position, reactor **N** or **R** for the normal or the reverse position, respectively, of a track switch, which is in turn preceded by a reference character number for the switch.

The circuits for energizing each of the route selector relays **1ANS**, **1RS** and **1BNS** are arranged for storing the control for the corresponding route if a leverman pushes the buttons for setting up the corresponding route while the switches are locked because the extended locking section for that route is occupied, although the switch sections **A1T** and **B1T** are unoccupied.

In Fig. 1c, a first switch locking relay, designated by the reference character **1LR**, is shown controlled by approach or time locking relays designated by the reference characters **2AS**, **4AS**, **6AS** and **8AS**, and by switch section track relays **A1R** and **B1R**. Relays **2AS**, **4AS**, **6AS** and **8AS** may be controlled similarly to relay **2AS** shown in Fig. 1F of the Lewis patent referred to.

A second switch locking relay, designated by the reference character **1LS**, is controlled by the first switch locking relay **1LR**, and by extended locking section track relay **6R** if the switches are reversed and signal **10** is controlled to display a

proceed indication, or by extended locking section track relay **8R** if the switches are normal and signal **10** is controlled to display a proceed indication, as well as by a switch lever **1V** having a middle position **c**. Lever **1V** has also reverse positions **n** and **r** for effecting operation of switches **A1** and **B1** to normal and reverse positions, respectively.

A polarized lever repeater relay **1VP** is controlled by relay **1LS** and by lever **1V**, and also by the route selector and exit stick relays.

Circuits are shown including contacts of relays **1LS** and **1VP** for controlling polarized switch control relay **1W**.

Normal and reverse switch repeater relays **1NC** and **1RC**, respectively, are shown controlled by polarized switch control relay **1W** and by polarized switch indication relay **1P**.

Normal and reverse switch indication relays **1NWK** and **1RWK**, respectively, are controlled by relays **1NC** and **1RC**, and by relay **1W**.

Circuits are also shown in Fig. 1c for controlling approach locking stick relay **10AS** associated with signal **10**.

In Fig. 1d, a track model or diagram is shown divided into indication sections including sections **1RK** and **1BNK**. Push buttons **2P**, **4P**, **6P** and **8P** are arranged in the track model at points corresponding to the locations of signals **2**, **4**, **6** and **8**, respectively, in the layout of Fig. 1a.

In Fig. 1e, circuits are shown controlled by a coding device **CD** for controlling indication lamps **1BNE** and **1RE** for sections **1BNK** and **1RK**, respectively, to display a flashing indication if the indication selector relay **A1SP** is deenergized and the switches of a corresponding route are locked in a given position because of a train on one of the extended locking sections, so that relay **1LS** is deenergized while relay **1LR** is energized.

Having described, in general, the arrangement and control of the apparatus shown by the accompanying drawings, I shall now describe, in detail, its operation.

As shown by the drawings, all parts are in their normal condition, that is, switches **A1** and **B1** are in their normal positions; all signals are indicating stop; all track sections are unoccupied, and hence the track relays are energized; lever **1V** is in its center position **c**; lever **10V** is in its normal position **n**; the controllers operable by buttons **2P**, **4P**, **6P** and **8P** are in their biased mid stroke positions; relays **2AS**, **4AS**, **6AS**, **8AS**, **10AS**, **1LR**, **1LS** and **1NC** are energized; relay **1P** is energized by current of normal polarity; coding device **CD** is intermittently energized; and relays **10H**, **1VP**, **1W**, **1RC**, **1NWK**, **1RWK**, **A1SP**, and the route selector and exit stick relays shown in Fig. 1b are deenergized.

The circuit by which relay **1LR** is energized passes from terminal **B** of a suitable source of current, through contacts **11**, **12**, **13** and **14** of relays **2AS**, **4AS**, **6AS** and **8AS**, respectively, contacts **A1R**—**15** and **B1R**—**16**, and the winding of relay **1LR** to the other terminal **O** of the same source of current.

A pick-up circuit is closed for relay **1LS**, passing from terminal **B**, through contact **1LR**—**17**, contact **6R**—**18** in multiple with contact **1NC**—**19**, contact **8R**—**20**, winding of relay **1LS**, and contact **22** of lever **1V** in its **c** position, to terminal **O**. A pick-up circuit is also closed for relay **1LS**, passing from terminal **B**, through contacts **1LR**—**17** and **10AS**—**21**, winding of relay **1LS**, and contact **22** of lever **1V** to terminal **O**. Stick circuits are also closed for relay **1LS**, which are the same as

the pick-up circuits just traced except including contact 23 of relay 1LS instead of contact 22 of lever 1V.

Both a pick-up and a stick circuit are closed for energizing relay 10AS, the pick-up circuit 5 passing from terminal B, through contacts 10H—24, 10R—25 and A10R—26, and the winding of relay 10AS to terminal O. The stick circuit passes from terminal B, through contact 10H—24, front point of contact 28 of relay 10AS, and the winding of relay 10AS to terminal O.

Relay 1NC is energized by a circuit passing from terminal B, through contact 1P—29, contact 1P—30 closed in the left-hand position, winding of relay 1NC, and contact 31 of relay 1W closed in 15 the left-hand position, to terminal O.

Coding device CD is intermittently energized by a circuit including its own back contact 32.

I shall assume that a leverman decides to set up a route for a southbound train to proceed past signal 8 over switch B1 in the normal position. He will therefore push the button 8P, causing relay 1BNS to become energized by a circuit passing from terminal B, through contact B1R—33, contact 34 of the controller operated by button 8P, back point of contact 1BNN—35, winding of relay 1BNS, contact 4XS—38 in multiple with contact 1RN—39, contact 1RS—40, and the back point of contact 1RWK—41 to terminal O. Relay 1BNS, upon becoming energized, completes a stick circuit for relay 1BNS, which is the same as the pick-up circuit just traced for this relay except that it includes a circuit path through contact 36 of the controller operated by button 8P, and contact 37 of relay 1BNS, instead of the circuit path through contact 34 of the controller operated by button 8P, and the back point of contact 1BNN—35.

The leverman will then push button 4P. Relay 4XS will therefore become energized by its pick-up circuit passing from terminal B, through contact 42 of the controller operated by button 4P, front point of contact 1BNS—43, contacts 1RN—44 and 1BNN—45, and the winding of relay 4XS to terminal O. Relay 4XS, upon becoming energized, completes its own stick circuit passing from terminal B, through contact 1BNS—46, contact 48 of relay 4XS, and the winding of relay 4XS to terminal O.

With relays 1BNS and 4XS energized, a circuit is completed for energizing relay 1VP by current of normal polarity, this circuit passing from terminal B, through contact 49 of relay 1LS, left portion of the winding of relay 1VP, and contacts 1BNS—50 and 4XS—51 to terminal O. The closing of this circuit causes no change in the position of contacts 52 and 55 of relay 1VP which are already in the normal position.

Relay 1W, however, is now energized by a normal control circuit passing from terminal B, through contact 52 of relay 1VP in the left-hand position, front point of contact 53 of relay 1LS, winding of relay 1W, front point of contact 54 of relay 1LS, contact 55 of relay 1VP in the left-hand position, and contacts 1BNS—50 and 4XS—51 to terminal O.

Relays 1P and 1NC are already energized as previously described.

With relay 1W energized, relay 1NWK now becomes energized by a circuit passing from terminal B, through contact 1W—56, front point of contact 57 of relay 1NC, and the winding of relay 1NWK to terminal O.

Signal 8 will now be cleared by circuits which are similar to the circuits shown for control-

ling the signals in the Lewis patent referred to. Relay 8AS will therefore become deenergized, causing relay 1LR to also become deenergized. Relay 1LR, upon becoming deenergized, causes relay 1LS to become deenergized.

The normal control circuit for relay 1W, through contacts 53 and 54 of relay 1LS, will now be opened, and a normal retaining circuit for this relay will be closed, passing from terminal B, through contact 1W—58 closed in the left-hand position, contact 1P—59 closed in the left-hand position, back point of contact 53 of relay 1LS, winding of relay 1W, back point of contact 54 of relay 1LS, and contact 1P—60 closed in the left-hand position to terminal O.

I shall now assume that a southbound train passes signal 8 and enters section B1T. Relay B1R will therefore become deenergized, and hence contact B1R—33 will be opened in the stick circuit previously described for relay 1BNS, causing relay 1BNS to become deenergized. With relay 1BNS deenergized, the stick circuit previously traced for relay 4XS will be opened at contact 1BNS—46, and hence relay 4XS will also become deenergized. The circuit for relay 1LR will now be opened at contact B1R—46, so that although relay 8AS becomes energized as the train enters section B1T, relay 1LR will remain deenergized, and therefore relay 1LS will also remain deenergized.

When the train enters section 8T, contact 8R—20 in some of the pick-up and stick circuits traced for relay 1LS will also be opened.

When the train leaves section B1T, relay 8AS having already become energized on account of the arm of signal 8 being returned to the stop position, relay 1LR will again become energized by its circuit previously traced. Relay 1LS will now become energized by its pick-up circuit including contact 10AS—21 if signal 10 has not been cleared.

I shall further assume that, while the train has been proceeding over the route controlled by signal 8, signal 10 has been cleared by the leverman moving lever 10V to its r position. Relay 10H is therefore energized by its circuit passing from terminal B, through contact 61 of lever 10V closed in the r position, contacts 6R—62 and 1NC—66, contact 67 of relay A1R, contact 68 of relay 10R, and the winding of relay 10H to terminal O. With relay 10H energized, the arm of signal 10 is operated to the proceed position by a circuit including contact 69 of relay 10H. Relay 10H, upon becoming energized, opens its contact 10H—24 in the circuits for relay 10AS, causing relay 10AS to become deenergized. With relay 10AS deenergized, contact 10AS—21 will be opened in the circuits for relay 1LS, causing relay 1LS to remain deenergized or to become deenergized, while the train is occupying section 8T, according as the train is still occupying section B1T or has left this section.

I shall next assume that, after the train leaves section B1T and while it is still occupying section 8T while sections A1T and 6T are unoccupied, the leverman decides to arrange for a route, controlled by signal 6, over switches A1 and B1 reversed. As already described, relay 1LR has become energized by its circuit previously traced when the train left section B1T. Switches A1 and B1 are now locked in their normal positions because relay 1LS is deenergized.

However, with relays 1NWK and 1LR energized, the leverman can energize relay 1RS by

depressing button 6P. The circuit by which relay 1RS becomes energized passes from terminal B, through contact A1R-70, contact 71 of the controller operated by button 6P, back point of contact 1RN-72, winding of relay 1RS, contact 2X-80, contact 81 of relay 4XS, contacts 1ANN-82 and 1BNS-83, front point of contact 1NWK-84, and contact 1LR-85 to terminal O. Relay 1RS, upon becoming energized, completes a stick circuit for relay 1RS which is the same as the pick-up circuit just traced except that it includes contact 74 of the controller operated by button 6P and contact 79 of relay 1RS instead of contact 71 of the controller operated by button 6P and the back point of contact 1RN-72.

The leverman will then depress push button 4P, thereby completing a second pick-up circuit for relay 4XS which is the same as the pick-up circuit previously traced for this relay except that it includes the back point of contact 1BNS-43 and the front point of contact 1RS-86 instead of the front point of contact 1BNS-43. A stick circuit for relay 4XS will then be completed which is the same as the stick circuit previously traced for this relay except that it includes contact 1RS-47 instead of contact 1BNS-46.

To inform the leverman that switches A1 and B1 are locked in the normal position because of the train on the extended locking section 8T, and that they can therefore not, at this time, be operated to the reverse position in response to his operation of buttons 6P and 4P for arranging the route governed by signal 6, indication lamp 1BNE will become lighted, and display a flashing indication, by a circuit passing from terminal B, through contact 87 of coding device CD, contacts 1LS-88, 1LR-89, 1NWK-90, and 1BNN-91, the back point of contact 92 of relay A1SP, and lamp 1BNE to terminal O.

The reverse control for switches A1 and B1 will be stored by relays 1RS and 4XS, and relay 10H will remain energized because contact INC-66 will remain closed, and hence signal 10 will continue to display the proceed indication.

As soon as the train leaves section 8T, relay 1LS will become energized by its pick-up circuit including contact 8R-20, previously traced. With relay 1LS energized, its contact 1LS-88 will open, and will thereby extinguish lamp 1BNE. With relay 1LS energized, a circuit will now be completed for energizing relay 1VP by current of reverse polarity, this circuit passing from terminal B, through contact 49 of relay 1LS, right-hand portion of the winding of relay 1VP, and contacts 1RS-93 and 4XS-94 to terminal O. 50

Contacts 52 and 55 of relay 1VP will therefore become closed in the right-hand position, thereby completing a circuit for energizing relay 1W by current of reverse polarity, this circuit passing from terminal B, through contact 55 of relay 1VP closed in the right-hand position, front point of contact 54 of relay 1LS, winding of relay 1W, front point of contact 53 of relay 1LS, contact 52 of relay 1VP closed in the right-hand position, and contacts 1RS-93 and 4XS-94 to terminal O. With relay 1W energized by current of reverse polarity, switches A1 and B1 will be operated to the reverse positions by the mechanisms A1M and B1M which will be energized by circuits passing from terminal B, through contact 70 70 1W-97, and through contact 1W-98 closed in the right-hand position, as indicated in Fig. 1a.

Upon completion of the operation of switches A1 and B1 to the reverse positions, relay 1P will become energized by current of reverse polarity. 75

Relay 1NC will become deenergized when relay 1W becomes energized by current of reverse polarity, and relay 1RC will become energized, when relay 1P also becomes energized by current of reverse polarity, by a circuit passing from terminal B, through contact 1P-29, contact 1P-30 closed in the right-hand position, winding of relay 1RC, and contact 31 of relay 1W closed in the right-hand position to terminal O.

- 10 Relay 1NWK will now be deenergized, and relay 1RWK will become energized by a circuit passing from terminal B, through contact 1W-56, back point of contact 57 of relay 1NC, contact 95 of relay 1RC, and the winding of relay 1RWK to terminal O. Relay A1SP will then become energized by a circuit passing from terminal B, through contacts 6AS-99 and 1RWK-100, and the winding of relay A1SP to terminal O. With relay A1SP energized, a circuit, only a portion of which is shown, including the front point of contact 101 of relay A1SP, will be completed for energizing lamp 1RE to display a steady indication.

During the operation of switches A1 and B1 to the reverse positions, relay 10H will remain energized on account of contacts 6R-62 and 8R-64, and contact 65 of relay B1R being closed, and hence signal 10 will continue to display the proceed indication.

30 Although I have herein shown and described only one form of apparatus embodying my invention, it is understood that various changes and modifications may be made therein within the scope of the appended claims without departing 35 from the spirit and scope of my invention.

Having thus described my invention, what I claim is:

1. In interlocking control apparatus for a first route extending from a given home signal along a given railway track over a given switch in the normal position and for a second route extending from said home signal over said switch in the reverse position, including a switch section in which said switch is located and a first and a second extended locking section in said first and said second route respectively beyond said switch section, including an approach signal for said home signal controlled over said first or said second extended locking section if said switch is in the normal or the reverse position respectively, the combination comprising, a first locking relay for said switch, a circuit for energizing said first locking relay if said switch section is unoccupied and said home signal indicates stop, a second locking relay for said switch, means controlled by a front contact of said first locking relay for energizing said second locking relay if said first extended locking section is unoccupied or said switch is in the normal position and if said second extended locking section is unoccupied or said switch is in the reverse position, and manually controllable means effective if said first locking relay is energized for preparing a circuit for effecting operation of said switch as soon as said second locking relay becomes energized.

2. In interlocking control apparatus for a first route extending from a given home signal along a given railway track over a given switch in the normal position and for a second route extending from said home signal over said switch in the reverse position, including a switch section in which said switch is located and a first and a second extended locking section in said first and said second route respectively beyond said switch section, including an approach signal for said

home signal controlled over said first or said second extended locking section if said switch is in the normal or the reverse position respectively, the combination comprising, a locking relay for said switch, means for energizing said locking relay if said switch section is unoccupied and if said first extended locking section is unoccupied or said switch is in the normal position and also if said second extended locking section is unoccupied or said switch is in the reverse position, and manually controllable means effective if said switch section is unoccupied for preparing a circuit for effecting operation of said switch as soon as said locking relay becomes energized.

3. In interlocking control apparatus for a first route extending from a given home signal along a given railway track over a given switch in the normal position and for a second route extending from said home signal over said switch in the reverse position, including a switch section in which said switch is located and a first and a second extended locking section in said first and said second route respectively beyond said switch section, including an approach signal for said home signal controlled over said first or said second extended locking section if said switch is in the normal or the reverse position respectively, the combination comprising, manually controllable means for energizing route control apparatus for each of said routes if said switch section is unoccupied, and means controlled by the route control apparatus for each of said routes for then setting up the corresponding route when its extended locking section becomes unoccupied.

4. In interlocking control apparatus for a first route extending from a given home signal along a given railway track over a given switch in the normal position and for a second route extending from said home signal over said switch in the reverse position, including a switch section in which said switch is located and a first and a second extended locking section in said first and said second route respectively beyond said switch section, including an approach signal for said home signal controlled over said first or said second extended locking section if said switch is in the normal or the reverse position respectively, the combination comprising, manually controllable means for energizing route control apparatus for each of said routes and for then retaining it in the energized condition if said switch sec-

tion is unoccupied, and means controlled by the route control apparatus for each of said routes for then setting up the corresponding route when its extended locking section becomes unoccupied.

5. In interlocking control apparatus for a first route extending from a given home signal along a given railway track over a given switch in the normal position and for a second route extending from said home signal over said switch in the reverse position, including a switch section in which said switch is located and a first and a second extended locking section in said first and said second route respectively beyond said switch section, including an approach signal for said home signal controlled over said first or said second extended locking section if said switch is in the normal or the reverse position respectively, the combination comprising, manually controllable means for energizing route control apparatus for each of said routes if said switch section is unoccupied, indication means controlled to display a flashing indication if said switch section is unoccupied and if one of said extended locking sections is occupied, and means controlled by the route control apparatus for each of said routes for setting up the corresponding route when its extended locking section becomes unoccupied.

6. In interlocking control apparatus for a first route extending from a given home signal along a given railway track over a given switch in the normal position and for a second route extending from said home signal over said switch in the reverse position, including a switch section in which said switch is located and a first and a second extended locking section in said first and said second route respectively beyond said switch section, including an approach signal for said home signal controlled over said first or said second extended locking section if said switch is in the normal or the reverse position respectively, the combination comprising, manually controllable means for energizing route control apparatus for each of said routes if said switch section is unoccupied and if said home signal indicates stop, and means controlled by the route control apparatus for each of said routes for then setting up the corresponding route when its extended locking section becomes unoccupied.

RONALD A. McCANN.
